(57) CLAIM

The ornamental design for a bottle, as shown and described.

DESCRIPTION

FIG. 1 illustrates a top, front, left side perspective view of a bottle showing my new design;

FIG. 2 illustrates a front elevation view thereof, wherein the rear elevation view is an identical image of this view;

FIG. 3 illustrates a right side elevation view thereof, wherein the left side elevation view is an identical image of this view;

FIG. 4 illustrates a top view thereof; and,

FIG. 5 illustrates a bottom view thereof.

The broken lines in the drawings illustrate the portions of the design that form no part of the claim.
